(57) **CLAIM**

The ornamental design for a microfluidic device, as shown and described.

DESCRIPTION

FIG. 1 is a perspective view of a microfluidic device, showing our new design;

FIG. 2 is a bottom plan view of the microfluidic device shown in FIG. 1;

FIG. 3 is a top plan view of the microfluidic device shown in FIG. 1;

FIG. 4 is a front elevation view of the microfluidic device shown in FIG. 1;

FIG. 5 is a rear elevation view of the microfluidic device shown in FIG. 1;

FIG. 6 is a left side elevation view of the microfluidic device shown in FIG. 1;

FIG. 7 is a right side elevation view of the microfluidic device shown in FIG. 1;

FIG. 8 is an enlarged view of the portion of the microfluidic device shown within the area designated as 8 in FIG. 1;

FIG. 9 is a bottom plan view of the portion of the microfluidic device shown in FIG. 8;

FIG. 10 is a cross-sectional view taken at line 10-10 of FIG. 8;

FIG. 11 is a cross-sectional view taken at line 11-11 of FIG. 8;

FIG. 12 is an enlarged view of the portion of the microfluidic device shown within the area designated as 12 in FIG. 1;

FIG. 13 is a bottom plan view of the portion of the microfluidic device shown in FIG. 12;

FIG. 14 is a cross-sectional view taken at line 14-14 of FIG. 12; and,

FIG. 15 is a cross-sectional view taken at line 15-15 of FIG. 12.

The broken lines in the drawings depict portions of the microfluidic device that form no part of the claimed design. The curved dashed lines in the middle of the microfluidic device depict break lines. The break lines and the areas between the break lines form no part of the claimed design. The dot-dot-dash lines in the drawings depict the boundaries of the enlarged views that form no part of the claimed design.

1 Claim, 10 Drawing Sheets
